CURRENT COLLECTING MEANS FOR TOY VEHICLES

Joseph L. Bonanno, Madison, N. J., assignor to The Lionel Corporation, New York, N. Y., a corporation of New York

Application October 15, 1949, Serial No. 121,496

11 Claims. (Cl. 191—49)

1 The present invention relates to current collecting means for toy vehicles and is more particularly directed toward current collecting means for toy locomotives. Toy locomotives used on the usual three-rail toy railroad track are ordinarily provided with driving wheels carried on the track rails and supporting the locomotive through axles and with current collecting devices cooperable with a central, third or power rail. The motor, headlight and other accessories carried on the locomotive are connected between the third rail current collector and the axles to complete the circuit.

The present invention contemplates improvements in the current collectors cooperable with the third rail as well as current collectors cooperable with the axles, and a unitary construction suitable for collecting current from the power and return rails.

According to the present invention, the toy vehicle is provided with a housing made of two insulated parts adapted to be secured together, and this housing encloses all the electrical parts of the vehicle and carries current collecting devices whereby current can be received from the axles and from the power rail. The conducting parts are all housed between and retained in place by the insulating housing parts forming the vehicle. Their assembly is readily accomplished without the use of tools.

Other and further objects of the invention appear as the description progresses.

The accompanying drawings show, for purposes of illustrating the present invention, one embodiment in which the invention may take form, it being understood that the drawings are illustrative of the invention rather than limiting the same.

In the accompanying drawings:

Figure 1 is a side elevational view showing one of the housing parts of the toy locomotive with all the conducting elements in place for collecting current, this view being taken in the direction of the arrow 1 of Fig. 2;

Figure 2 is a horizontal view taken on the line 2—2 of Fig. 1, showing both of the housing parts in position, with the current collecting devices therebetween; and

Figures 3 and 4 are vertical sectional views on the lines 3—3 and 4—4, respectively, of Fig. 1.

The locomotive propulsion unit P has a housing composed of two plastic moldings designated generally as 20 for the right housing and 21 for the left housing. These housings are of generally rectangular shape.

2 The right housing part 20 has a vertical side wall 22, bottom wall 24, front wall 25 and rear wall 26, all terminating in a common plane. The bottom wall 24 is recessed as indicated at 27, 27 and centrally of these recesses carries lugs 28, 28. Slightly higher up the side wall 22 are openings 29, 29 for the axle shafts. Adjacent the holes 29, 29 are forwardly extending lugs 31, 31 and intermediate these lugs is another forwardly extending lug 32. Above and to the side of the lug 32 are two forwardly extending lugs 33, 33. The recesses 27, 27 and lugs 28, 28 are adapted to receive current collecting rollers 34, 34. The rollers are in the form of strips of sheet metal 15 bent to tubular shape. Conducting strap 35 bears on these rollers and is held in place by the lug 32 and a rib 32' below the lug 32 entering notch 35'. The strip 35 is resilient and yields when the rollers are on the third rail. The holes 29 receive the wheel axles 36, 36. A resilient conducting strip 37 bears on the axles 36, 36 and extends between the upper face of lug 32 and the lower faces of lugs 33, 33, so that current can be carried from the power and wheel bearing rails 20 into the locomotive housing. When the axles are out, the contact strip 37 bears on top of lugs 31. It has a bent extension 38 held back by a filter strip 62, and its ends are bent up as indicated at 37' to facilitate inserting the axles. The conducting strips 35 and 37 are connected to a load such as motor 40.

The left housing part 21 of similar configuration has recesses 85 to meet dowel-like pins 88 extending forwardly from the housing part 20. The housing part 21 is recessed as indicated at 87, 87 and provided with lugs 88 opposite the recesses 27 and lugs 28 of the housing part 20 so as to keep the contact rollers 34 in place. It has axle openings 89 opposite axle openings 29. It has a lug 91 opposite to but higher than lug 32 and rib 91' opposite the rib 32' to hold the strips 35 and 62 in place. The housing parts are secured together by spring clips not shown.

The axles carry wheels 100 adapted to support the locomotive on the track rails 101 and 102. When so placed on the rails, the contact rollers 34 are on power rail 103 and are lifted up as shown in Figure 4 to bend the ends of spring 35. This insures good contact with the third rail and as the rollers have freedom of movement in all directions, they have very long life. The roller type third rail contacts are suitable for use on various toy railroad vehicles.

The complete locomotive with which the present current collectors are more especially adapt-

ed to be used is shown in co-pending application, Serial No. 121,494 filed concurrently herewith.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. In a toy railroad vehicle, a current collector for use with the power rail of a toy railroad track, comprising a hollow cylindrical sheet metal roller, a horizontally extending support of smaller size than the inner diameter of the roller and projecting into the roller, side members limiting sidewise movement of the roller, and a conducting leaf spring bearing on the top of the roller.

2. A current collector for a toy railroad vehicle as claimed in claim 1, wherein the roller is in the form of a strip of sheet metal rolled to cylindrical form.

3. A current collector for a toy railroad vehicle as claimed in claim 1, wherein the horizontal support and the side members are embodied in two inwardly facing insulating housing members, and the fixed end of the spring is interlocked between the housing members.

4. A current collector for a toy railroad vehicle comprising a horizontal tubular contact, a contact support including side members having extensions protruding into the tube, the side members being close to the ends of the tube to keep it positioned along its axis, the extensions being smaller than the inside diameter of the tube so that the tube may move up and down, and being spaced above the lower faces of the members such that the tube in its lower position is exposed, and a contact spring bearing on the upper surface of the tubular contact to hold it down against the top of the extensions and yield when the tubular contact is moved upwardly.

5. A current collector for a toy railroad vehicle as claimed in claim 4, wherein the lower faces of the extensions are above the lower faces of the side members to allow the tubular contact to be received between the side members.

6. A toy vehicle having a housing comprising two insulating parts facing one another, the housing having a bottom wall with two downwardly opening passages intersected by the joint between the housing parts and interrupted by horizontal lugs, a tubular contact roller received in each passage and held against removal by the lugs, the lugs being smaller than the tubular contacts so that the rollers may have limited up and down movement, and housing carried spring means bearing on the top of each contact roller to hold it down against the lugs.

7. A toy vehicle having a housing comprising two insulating parts facing one another, the

housing having a bottom wall with two downwardly opening passages intersected by the joint between the housing parts and interrupted by horizontal lugs, a tubular contact roller received in each passage and held against removal by the lugs, the lugs being smaller than the tubular contacts so that the rollers may have limited up and down movement, and a leaf spring having ends bearing on the top of the contacts and a central portion interlocked between the housing parts against upward, endwise, or lateral movement.

8. A current collector for a toy railroad vehicle, comprising a contact roller in the form of a horizontal tube, supporting members lateral of the tube spaced slightly more than the length of the tube and having lugs entering the tube, the lugs being of smaller vertical depth and length than the inside diameter of the tube, whereby the roller is free for rolling and for limited movement up and down, forward and back and for tilting, and a spring bearing on the roller to urge it downwardly against the lugs.

9. In a toy vehicle, two insulating housing parts on opposite sides of a median vertical plane lengthwise of the vehicle, facing one another and having opposed cavities to form contact receiving spaces, opposed axle openings, and opposed contact roller receiving recesses in the bottom wall opening into the contact receiving cavities to form vertical passages, the recesses having lugs projecting toward one another and partly interrupting the passages, axles extending through the axle openings, a resilient contact strip traversing the cavities, held in place by engagement with the housing parts and bearing on the axles, a second resilient contact strip traversing the cavities, held in place by engagement with the housing parts and terminating adjacent the lugs, and contact rollers projecting downwardly through the passages, the rollers being carried on the lugs and pressed downwardly by the second contact strip.

10. A toy electric railroad vehicle having a body formed of two insulating housing parts provided with aligned axle openings and opposed cavities to form contact receiving spaces, wheel carrying axles carried in the axle openings, and a resilient current conducting strip held in place between the housing parts and having ends bearing on the axles inside the housing to provide conductive connection therebetween.

11. A toy electric railroad vehicle as claimed in claim 10, wherein the body has lugs to limit the movement of the spring when the axles are removed.

JOSEPH L. BONANNO.
